UNITED STATES PATENT OFFICE.

RICHARD WEBB BURNETT, OF MONTREAL, QUEBEC, CANADA.

CONVERTIBLE CAR.

1,081,430.

Specification of Letters Patent.

Patented Dec. 16, 1913.

Application filed October 17, 1911. Serial No. 655,253.

To all whom it may concern:

Be it known that I, RICHARD WEBB BURNETT, a citizen of the United States of America, residing at the city of Montreal, Province of Quebec, Dominion of Canada, have invented certain new and useful Improvements in Convertible Cars; and I do hereby declare that the following is a full, clear, and exact description thereof.

10 My invention relates particularly to cars for carrying loose commodities such as grain, coal, gravel, and the like, and it has for its object to simplify the construction of the car as a carrier for loose commodities, 15 to simplify and render more effective the seal and locking device for the dumping doors, to simplify and form as a component, part of the car as a general freight carrier, the grain door adjustable in height to meet 20 the usual requirements, and to prevent the lodgment of water in the vicinity of the dump door lock.

The invention may be said to consist of the construction and several combinations 25 and arrangements of parts hereinafter described and pointed out in the claims.

For full comprehension, however, of my invention reference must be had to the accompanying drawings forming a part of this 30 specification in which similar reference characters indicate the same parts, and wherein:

Figure 1 illustrates diagrammatically a transverse vertical sectional view of a convertible car containing my invention, with 35 the parts arranged for service as a general freight carrier, the view being taken on line A A Fig. 3; Fig. 2 is a similar view to Fig. 1 of one-half only of the car, however, and drawn to a larger scale, the parts being arranged 40 for service as a general freight-carrier, and shown in dotted lines as arranged for a grain carrier; Fig. 3 is a side elevation of the middle portion of the car arranged as a grain carrier; Fig. 4 is a detail 45 perspective view of the locking device for the discharge door; Fig. 5 is a detail sectional view of one of the end walls of the discharge hopper, taken on line C C Fig. 2; Fig. 6 is a longitudinal sectional view of the 50 combined floor and grain door in position as a floor member, the view being taken on line D D Fig. 2; Figs. 7 and 8 are perspective views of the dump door hinge illustrating the same in open and closed positions respectively; Fig. 9 is a detail perspective view 55 of parts of the combined floor and grain door

and the portion of the fixed floor with which it is in hinged relation; Fig. 10 is a perspective view of the device for pressing the dump door upon its jamb; and Fig. 11 is a horizontal sectional view taken on line B B Fig. 3.

My improved car has a pair of hoppers disposed transversely and each consisting of a pair of vertical walls 2, 2, and a fixed inclined floor member, the latter being formed by the end portions of a plate member extending transversely to within comparatively close proximity of the sides of the car, the middle of this member resting 70 on the center sill and being shaped to present oppositely facing angular door jambs 4, 4. It consists, preferably, of a pair of plates 5, 5 constituting the fixed floor members of the hoppers, and the door-jamb portion is preferably formed of a separate metal plate 6 bent to the form required, the edges of all three plates being riveted together and to the center sill as at 7. The end edges of these inclined floor members 80 are attached to the bottom edges of the vertical side walls 2, 2 thus forming chutes, the discharge mouths of which are disposed in angular positions slightly removed from the perpendicular plane of the sides of the car. 85 Relatively small doors 10 close the mouths of these chutes, and like these mouths are when closed in positions inclined only slightly from the vertical.

Each dump door consists of the door 90 member proper 12 with end flanges 13 toward the door-frame formed by the fixed diagonal floor member and the vertical walls of the hopper, and a stiffening flange 14 extends along the free edge thereof, the door being hinged to the fixed diagonal floor member and the edges of door and hopper floor in juxtaposition and the engaging portion of the door and door frame together with the discharge doors themselves, means for locking the doors and the loading doors being all of particular construction contributing to the fulfilment of the principal object of my invention, viz. to produce a simple, effective and economical car which, while grain tight, will be sufficiently strong to carry coal, ore, gravel and other ponderous loose commodities. To this end the discharge doors 12 are, as before mentioned, disposed in easy angular positions relatively to the vertical thus subjecting them to minimum load and conse-

quently permitting them to be made of light weight material, which, in addition to their small size, enables doors to be provided which can be manually operated without 5 the more or less cumbersome, and, in some cases, complex door-closing mechanism now in use, locking mechanism only being required.

The door locking mechanism I prefer to 10 use embodies clamping as well as locking properties, and consists of a bar 25 journaled in angular brackets 26 fastened at the opposite ends of each door to the side-sills 27 of the under-framing of the car. 15 Each bar has preferably forged thereon a handle 28 and a series of preferably three, presser-feet 29 adapted to bear upon the door and press it tightly against the door-jamb formed by an angle iron 36 fastened 20 to the underside of the side-sills 27. One of the presser-feet is formed integrally with the handle, and a bracket 30 with holes 31 therein to receive a retaining cotter pin 32, is fastened to the door and affords means 25 for locking the handle bar, presser-feet and door tightly and effectively closed against leakage of grain and with sufficient strength to withstand the maximum load to which it may be subjected when the car is loaded 30 with coal, ore and the like. These presser-feet are each preferably of return-bend form, as shown, to accommodate the stiffening flange of the door and downwardly inclined flanges 35 presented by obtuse angle-irons riveted to the outer faces of the side sills at the lower edges thereof. These flanges serving as water-sheds protecting the upper edges of the doors when closed and the cotter pin serves as a means for 40 sealing the door. The hinges for connecting these discharge doors to the inclined floor members consist of straps 40 fastened to the doors and floor-members and hinge rods 41 uniting them, and devices distinct 45 from the hinge proper, for providing an effective grain tight joint between the parts held in juxtaposition by the hinge consist of coinciding flat surfaces presented by a flange 42 upon the floor-member and one of 50 the faces presented by the interior of a pocket 43 in the door formed by bends 44 and 45 surrounding the flange 42, the angular position of which is such as to be cleared by the door when swinging to open 55 position. It is to be observed that the particular arrangement of these faces prevent the commodity lodging thereon.

In order to prevent leakage of granular materials at the ends of the doors, when 60 closed pockets to receive the flanges 13 of the latter are formed in the discharge edges of the vertical walls 2 of the hoppers, offset plates 50 being riveted or otherwise rigidly secured along the outer sides of these 65 walls at and parallel with the edges thereof,

for the purpose. The pockets provided by the offset-plates and walls are just sufficient to receive the flanges 13 without space for the leakage of the finest granular substance such as sand or even flour, and the same effective seal is afforded, as shown above, at the hinged and locking edges of the door. Check chains 55 sustain the doors in proper position when open.

A serious defect in cars of this type has 75 been the misfit of the floor members and the unavailability of the grain-doors when required. I overcome these defects by providing a displaceable telescopic floor member adapted to displace any grain and the 80 like left on the center sill or other members of the underframe on which these displaceable floor members rest. The specific device for the purpose comprises a member 60 made up of tongue-and-groove boards 85 arranged longitudinally with relation to the car, and fastened together by metal bands 69 on opposite sides of this door member and braced by a series of angle-irons 61 half of the length of each of which is riveted in 90 place and the remainder sprung out slightly as at 62 to accommodate the extensible member to be presently further alluded to. This floor member is hinged to the fixed floor members 63 of the car by means of trunnions 65 fastened to the floor by plates 66 to which they are welded, such plates being riveted or bolted in place, and a plate 67 of half D form with its angle disposed so as to bear on the top of the side sill and 100 against a threshold strip 68 when the member 60 is raised and thus act as a grain seal, and, at the same time, serve as a stop limiting the outward movement thereof and taking up some of the strain which otherwise would be carried entirely by the door frame in the side of the car. The trunnions are journaled in sockets beneath the contiguous edges of the fixed floor members 105 in which are mounted offset plates 70 confining the trunnions between them, the side of the car-body and the top of the side sill. The fixed floor members are securely fastened in place by being bolted or riveted as 110 at 75 to the underframing. The free edges of these members 60 are beveled to coincide and make contact with the diagonal jambs 4, 4, on the center sill. To impart to this displaceable floor member 60 all the properties of a grain-door and therefore enable 115 it to afford a large or small loading opening as required, it is provided with the extensible member before mentioned which is indicated at 80 and of trough form slidably 120 clasping the member 60 between it and the sprung portions of the angle-iron stiffeners. This extensible member is for use solely as 125 a door part and is telescoped within the limits of the main door member 60 when the latter serves as a floor member.

Guiding brackets 100 secured to the car-side afford means for retaining the extended grain-door in perpendicular position, and they are so located that the extensible member 80 must be pushed fully back before the member 60 can be lowered, thus insuring a proper location of the latter on the main door when it is dropped and obtaining a proper fit as part of the floor.

10 With the parts assembled as above described an effective and strong floor is provided for the car as a common freight carrier, when the greatest strains are exerted, and as a grain-door is effective as a grain seal, durable, light in weight, and always available, the discharge hoppers and doors are grain tight at all points and also durable and light in weight, and the complete structure is of sufficient strength to sustain 15 the strains exerted by the heaviest cargoes of loose commodities; furthermore, an advantageous feature of the enveloping flanges 50 of the vertical walls of the hoppers and the flanges on the door enveloped thereby, 20 is that it is impossible for leakage to occur of the finest granular loose commodity 25 owing to the sealing properties of these enveloping flanges.

The main member 60 of the combined 30 floor and grain-door is held in vertical position independently of the extensible section 80 and bracket, by a pair of latches 200 carried by plates 201 countersunk in the sides of the door posts.

35 The telescopic member is held up by bow-spring catches 205, riveted within recesses 207 therein, and sockets 206 in the top of the main member of the door are engaged by these catches.

40 I do not claim the locking device, the convertible grain-door and floor sections for a car, nor the features of the door jambs and particular formation of the doors for engaging the jambs to afford 45 convertible flat and hopper-bottom dumping car structure, as the said inventions form the subject-matter of separate applications as follows:—Car door locking device, filed July 11, 1912, Serial No. 710,265.

50 Convertible grain door and floor sections for

cars, filed July 11, 1912, Serial No. 710,266. Convertible flat and hopper bottom dumping cars, filed July 11, 1912, Serial No. 710,264.

What I claim is as follows:—

55

1. In a car for loose commodities the combination with a side sill and center-sill, of a discharge hopper comprising vertical walls hung from the car body, a diagonal hopper floor member carried by the walls 60 and extending substantially the full length and width of the hopper, a door hinged to the floor member and adapted to close to an angular position close to a vertical plane, and means for locking the free edge of the 65 door to the side sill.

2. In a car for loose commodities, a discharge hopper consisting of parallel vertical walls, a fixed diagonal floor member, and a door hinged to the discharge edge of 70 the floor member, each wall having secured thereon an offset plate forming therewith a pocket and the door having flanges adapted to be enveloped by the pockets when the door is closed, and means for supporting the 75 door in closed position.

3. In a car for loose commodities, the combination with the discharging door frame thereof one side of which has a part presenting a flat bearing surface and the opposite side has a flat surfaced door-jamb and the remaining sides have pockets extending throughout their length, of a trough door hinged to the door frame contiguous to the said bearing surface and having a surface 80 adapted to bear upon the same when the door is closed the free edge of the door simultaneously bearing upon the door-jamb and the flanges of the trough entering the 85 pockets and means for supporting the door 90 in closed position.

In testimony whereof I have signed my name to this specification in the presence of two witnesses.

Montreal October 5, 1911.

RICHARD WEBB BURNETT.
